PREPARATION OF SULPHATED FATTY ESTERS

Alton A. Cook, Glen Ridge, and Curt Tjorn and Joseph Zaparanick, Westfield, N. J., assignors to Arkansas Company, Inc., Newark, N. J., a corporation of New York

No Drawing. Application October 16, 1941,
Serial No. 415,218

15 Claims. (Cl. 260—400)

The present invention relates to the production of sulphated fatty esters and it particularly relates to the production of sulphated fatty esters for use in textile processes, or as textile agents.

It has not been found particularly satisfactory for example in forming sulphated esters, to first form an ester and then subsequently treat it with a strong sulphating or sulphonating agent.

For example, where butyl oleate or butyl ricinoleate are first prepared and then treated with sulphuric acid, most desirable results are not obtained.

This is also true in cases where mixtures of butyl alcohol and oleic acid are sulphonated or where butyl alcohol is first combined with sulphuric acid following which the butyl acid sulphate resets with the fatty acid.

Furthermore, many disadvantages have been observed in processes where the fatty acid glycerides are sulphonated in the presence of a low molecular weight aliphatic alcohol, as for example, where castor oil is sulphated or sulphonated in the presence of isopropyl alcohol as a solvent.

It is among the objects of the present invention to prepare improved sulphated or sulphonated fatty esters with greater yield and with a smaller production of undesirable by-products, which may be more readily and effectively used as penetrating, emulsifying, and washing agents, and generally as surface active agents particularly in the textile fields.

Another object is to provide an improved procedure for obtaining sulphonated or sulphated low molecular weight alkyl esters of high molecular fatty acids with enhanced yield.

Still further objects and advantages will appear from the more detailed description set forth below, it being understood, however, that this more detailed description is given by way of illustration since various changes therein may be made by those skilled in the art without departing from the scope and spirit of the invention.

In accomplishing the above objects it has been found most satisfactory to form the fatty esters by a series of steps, preferably two in number, which are most economically and satisfactorily carried out in succession.

According to the first step a low molecular weight alkyl fatty ester is formed from a low molecular weight alkanol such as methanol, ethanol, isopropanol or butanol and an unsaturated or hydroxy fatty acid, such as oleic, ricinoleic, erucic, and so forth, in the presence of a suitable catalyst such as an alkylated naphthalene sulphonate acid.

This reaction may be carried out at a temperature of 80° to 100° C., with refluxing, if necessary, and preferably with constant stirring or agitation for a period of 2 to 8 hours.

The preferred temperature for the reaction is 90° C. to 95° C., and the preferred time is from 4 to 6 hours, and generally when the reaction is carried on under these conditions there is a yield of ester amounting to 90% to 95%.

By the use of lower temperatures and shorter reaction periods esters of somewhat lighter color may be produced.

In all cases, however, it has been found most desirable to use molal proportions of alcohols and fatty acids, except in those cases where the alcohol is highly volatile. In such cases about 10% in excess over molal proportions may be used to cover possible losses.

15 The amount of catalyst usually found desirable for optimum results may range from 5% to 10% of the amount of the reaction mixture and when the reaction is completed the catalyst together with the water produced in the reaction may be permitted to settle out and drawn off if desired.

In this first step it is possible to use as the fatty acids:

25 Oleic
Linoleic
Linolenic
Eleostearic
Erucic
Ricinoleic
30 or the mixed fatty acids derived from the following oils:

35 Soy bean oil
Corn oil
Olive oil
Tea seed oil
Sperm oil
Fish oils
Rice bran oil
Grapefruit seed oil
40 Sunflower seed oil

As the low molecular weight alcohols there may be employed the following alcohols:

45 Methyl
Ethyl
Isopropyl or normal propyl
Isobutyl or normal butyl
Amyl
Hexyl
Octyl
50

or instead of these low molecular weight alcohols it is also possible to use their esters such as

55 Formates
Acetates
Propionates
Butyrates
Lactates
Citrates
Succinates
60

As the catalyst, generally any alkylated aromatic sulphonic acid may be employed, which is not darkening, among which acids may be alkylated or unalkylated aromatic sulphonic acids, such as methyl, ethyl, propyl, butyl, amyl or other alkylated benzene, toluene or naphthalene sulphonic acids.

Among the preferred compounds which may be employed are:

Mono butyl alpha naphthalene sulphonic acid
Beta naphthalene sulphonic acid
Para toluene sulphonic acid

Sulphuric acid itself is generally not utilized because of its darkening effect.

This first step appears to result in formation of low molecular weight alkyl esters of high molecular weight unsaturated or hydroxy fatty acids.

In the second step the ester which has been prepared in the first step above stated is cooled to a temperature of about 20° to 25° C., and a molal weight of a complex alcohol or ester having ether, ketone, or amino groups in the molecule is added per mol of fatty acid.

These complex alcohols or esters may be aliphatic, aromatic, or mixed types and among the complex alcohols or esters which have been found to be particularly suitable are the following groups and classifications:

- (1) Esters containing an ether grouping, such as diethyleneglycol monobutyl ether acetate.
- (2) Alcohols containing an ether grouping, such as the monobutyl ether of diethyleneglycol.
- (3) Alcohols or esters containing a ketone group, such as diacetone alcohol.
- (4) Alcohols containing amino groups such as monoethanolamine.

As preferred alcohols and esters which may be used:

Ethylene glycol monomethyl ether acetate (methyl "Cellosolve" acetate)
Ethylene glycol monoethyl ether acetate ("Cellosolve" acetate)
Ethylene glycol monobutyl ether acetate (butyl "Cellosolve" acetate)
Diethylene glycol monoethyl ether acetate ("Carbitol" acetate)
Diethylene glycol monobutyl ether acetate (butyl "Carbitol" acetate)
Ethylene glycol monomethyl ether (methyl "Cellosolve")
Ethylene glycol monoethyl ether ("Cellosolve")
Ethylene glycol monobutyl ether (butyl "Cellosolve")
Diethylene glycol monomethyl ether (methyl "Carbitol")
Diethylene glycol monoethyl ether ("Carbitol")
Diethylene glycol monobutyl ether (butyl "Carbitol")
Diethylene glycol dicresyl ether (dicresyl "Carbitol")
Diacetone alcohol

Among the preferred amino alcohols which may be used are:

Monoethanolamine
Diethanolamine
Triethanolamine
Phenylethanolamine
Hydroxyethyl ethylenediamine
Diethylaminoethanol
2 amino-2 methyl-1 propanol
Di n-butyl aminoethanol
Trimethylol aminomethane

The above mixture is then treated with a sulphating agent, preferably commercial 66° Bé. sulphuric acid at a temperature of 20° to 25° C. for 1 to 3 hours. The amount of sulphating agent should be at least 100% of the total weight of the reaction mixture and may be as high as 300%.

During this second step or reaction it appears that the larger or more complex radical replaces the smaller and simpler radical at least in part; that is, if methyl oleate, produced by the first reaction is treated with the monobutyl ether of diethylene glycol acetate, the radical "butyl ether diethylene glycol" appears to replace in part the "methyl" group in its combination with oleic acid.

After completion of the second reaction step, the resulting product is washed, preferably with a 10% to 20% solution of common salt, and then neutralized with caustic soda or any other suitable alkali.

In most cases a partial neutralization to a pH of between 5 and 7 is preferable.

The final products are clear, oily liquid of either an amber or a reddish color and give clear solutions in water, which have remarkable foaming properties, even at highly attenuated dilutions.

On the Standard canvas disc method for measuring efficiency of penetration, these products give considerably better results than sulphated esters produced by the other methods previously described.

To give some examples of various reagents which may be utilized, all parts being by weight:

EXAMPLE I	
First step	
35	Parts
Oleic acid	282
Methyl alcohol	35
Catalyst	25
40	Second step
	Parts
Methyl oleate	300
Diethyleneglycol monobutylether acetate	204
Sulphuric acid	600

EXAMPLE II	
First step	
50	Parts
Ricinoleic acid	298
Ethyl acetate	88
Catalyst	20
55	Second step
	Parts
Ethyl ricinoleate	370
Monoethanolamine	60
Sulphuric acid	500

EXAMPLE III	
First step	
55	Parts
Soya bean fatty acids	281
Anhydrous ethyl alcohol	50
Catalyst	20
60	Second step
	Parts

Ethyl soya bean fatty acid compound	309
Ethylene glycol monoethyl ether acetate	132
Sulphuric acid	500

EXAMPLE IV	
First step	
75	Parts
Rape seed fatty acids	303
Butyl alcohol	75
Catalyst	25

Second step		
Butyl rape seed	359	
Ethylene glycol mono butyl ether	118	
Sulphuric acid	500	
EXAMPLE V		5
First step		
Corn oil fatty acids	283	
Isopropanol	65	
Catalyst	20	10
Second step		
Isopropanol corn oil	325	
Diacetone alcohol	116	
Sulphuric acid	500	15
EXAMPLE VI		
First step		
Peanut oil fatty acids	278	20
Methanol	35	
Catalyst	20	
Second step		
Methyl peanut oil	292	
Hydroxy ethyl ethylene diamine	105	25
Sulphuric acid	600	
EXAMPLE VII		
First step		
Oleic acid	282	30
Butyl alcohol	75	
Catalyst	20	
Second step		
Butyl oleate	338	35
Diethylene glycol mono phenyl ether	138	
Sulphuric acid	600	
EXAMPLE VIII		
First step		40
Ricinoleic acid	298	
Methanol	35	
Catalyst	20	
Second step		45
Methyl ricinoleate	312	
Phenyl ethanolamine	137	
Sulphuric acid	600	

The above wetting agents are effective penetrants and can be used as emulsifying and detergents agents in dye baths and in scouring and other connections.

It is to be understood that the invention is not intended to be restricted to any particular example, composition or proportions, or to any particular application or to any specific manner of use or to any of various details thereof, herein described, as the same may be modified in various particulars or be applied in many varied relations without departing from the spirit and scope of the claimed invention, the practical embodiments herein described merely showing some of the various features entering into the application of the invention.

What is claimed is:

1. A process of preparing sulphated fatty acid esters which comprises first treating high molecular weight unsaturated fatty acids with a low molecular weight aliphatic monohydric alcohol in the presence of a catalyst and then treating the thus obtained product with a complex aliphatic alcohol selected from the group consisting of low molecular weight ether alcohols, keto alcohols, amino alcohols and the esters of these alcohols with low molecular weight fatty acids, in the presence of a sulphating agent.

2. A process of preparing sulphated fatty acid esters which comprises first treating high molecular weight unsaturated fatty acids with a low molecular weight aliphatic monohydric alcohol in the presence of a catalyst and then treating the thus obtained product with a complex aliphatic alcohol selected from the group consisting of low molecular weight ether alcohols, keto alcohols, amino alcohols and the esters of these alcohols with low molecular weight fatty acids, in the presence of concentrated sulphuric acid.

3. A process of preparing sulphated fatty acid esters which comprises first combining high molecular weight fatty acids with a low molecular weight aliphatic alcohol in the presence of an aromatic sulphonic acid and then combining the reaction mixture with an ether of a polyhydroxy low molecular weight aliphatic alcohol in the presence of a sulphating agent.

4. A process of preparing sulphated fatty acid esters which comprises first combining oleic acid with methyl alcohol in the presence of an aromatic sulphonic acid and then combining the reaction mixture with an ether of a polyhydroxy low molecular weight aliphatic alcohol in the presence of a sulphating agent.

5. A process of preparing sulphated fatty acid esters which comprises first combining high molecular weight fatty acids with a low molecular weight aliphatic alcohol in the presence of an aromatic sulphonic acid and then combining the reaction mixture with an ether of a polyhydroxy low molecular weight aliphatic alcohol selected from the group consisting of alkylene glycol mono-alkyl ethers in the presence of a sulphating agent.

6. A process of preparing sulphated fatty acid esters which comprises first combining high molecular weight fatty acids with a low molecular weight aliphatic alcohol in the presence of an aromatic sulphonic acid and then combining the reaction product with an alkanolamine in the presence of a sulphating agent.

7. A process of preparing sulphated fatty acid esters which comprises first combining high molecular weight fatty acids with a low molecular weight aliphatic alcohol in the presence of an aromatic sulphonic acid and then combining the reaction product with hydroxyethyl ethylene diamine in the presence of a sulphating agent.

8. A process of preparing sulphated fatty acid esters which comprises first treating high molecular weight unsaturated fatty acids with a low molecular weight aliphatic monohydric alcohol in the presence of an aromatic sulphonic acid and then treating the thus obtained product with a low molecular weight aliphatic acid ester of an ether of a polyhydroxy low molecular weight aliphatic alcohol in the presence of a sulphating agent.

9. A process of preparing sulphated fatty acid esters which comprises first treating high molecular weight unsaturated fatty acids with a low molecular weight aliphatic monohydric alcohol in the presence of an aromatic sulphonic acid and then treating the thus obtained product with an acetate of an alkylene glycol mono-alkyl ether in the presence of a sulphating agent.

10. A process of preparing sulphated fatty acid esters which comprises first combining high molecular weight fatty acids with a low molecular weight aliphatic alcohol in the presence of a

naphthalene sulphonic acid and then combining the reaction product with mono-ethanolamine.

11. A process of preparing sulphated fatty acid esters which comprises first treating oleic acid with methyl alcohol in the presence of naphthalene sulphonic acid as a catalyst and then treating the thus obtained product with a complex aliphatic alcohol selected from the group consisting of low molecular weight ether alcohols, keto alcohols, amino alcohols and their esters with low molecular weight fatty acids in the presence of concentrated sulphuric acid.

12. A process for preparing completely water soluble complex sulphated fatty acid esters, comprising first treating high molecular weight unsaturated fatty acids with a low molecular weight monohydric aliphatic alcohol in the presence of a suitable catalyst while maintaining a temperature of about between 80° C. to 100° C. for a period of about 2 to 8 hours and treating the hereby obtained ester in the purified freshly prepared state directly with a complex aliphatic alcohol selected from the group consisting of ether alcohols, keto alcohols, amino alcohols and the esters of these alcohols with low molecular weight fatty acids in the presence of a sulphating agent, the hereby produced complex sulphated fatty acid ester having wetting properties which are approximately three times as powerful than that obtained by a one step treatment of the commercially available ester.

13. A process for preparing completely water soluble complex sulphated fatty acid esters, comprising first treating high molecular weight unsaturated fatty acids with a low molecular weight monohydric aliphatic alcohol in the presence of a suitable catalyst while maintaining a temperature of about between 80° C. to 100° C. for a period of about 2 to 8 hours and treating the hereby obtained ester in the purified freshly prepared state directly with a complex aliphatic alcohol selected from the group consisting of ether alcohols, keto alcohols, amino alcohols and the esters of these alcohols with low molecular weight fatty acids in the presence of at least an equal quantity of a sulphating agent while maintaining a temperature of about 20° to 25° C. for a period of about 1 to 3 hours, the hereby produced complex

sulphated fatty acid ester having wetting properties which are approximately three times more powerful than that obtained by a one step treatment of the commercially available ester.

14. A process for preparing completely water soluble complex sulphated fatty acid esters, comprising first treating high molecular weight unsaturated fatty acids with a low molecular weight monohydric aliphatic alcohol in the presence of a suitable catalyst while maintaining a temperature of about between 80° C. to 100° C. for a period of about 2 to 8 hours and treating the hereby obtained ester in the purified freshly prepared state directly with a complex aliphatic alcohol selected from the group consisting of ether alcohols, keto alcohols, amino alcohols and the esters of these alcohols with low molecular weight fatty acids in the presence of a sulphating substance, neutralizing the final product with alkali to a pH of between about 5 and 7, the hereby produced complex sulphated fatty acid ester having wetting properties which are approximately three times more powerful than that obtained by a one step treatment of the commercially available ester.

15. A process for preparing completely water soluble complex sulphated fatty acid esters, comprising first treating high molecular weight unsaturated fatty acids with a low molecular weight monohydric aliphatic alcohol in the presence of alkylated aromatic sulphuric acid as a catalyst while maintaining a temperature of about between 80° C. to 100° C. for a period of about 2 to 8 hours and treating the hereby obtained ester in the purified freshly prepared state directly with a complex aliphatic alcohol selected from the group consisting of ether alcohols, keto alcohols, amino alcohols and the esters of these alcohols with low molecular weight fatty acids in the presence of a sulphating agent, the hereby produced complex sulphated fatty acid ester having wetting properties which are approximately three times more powerful than that obtained by a one step treatment of the commercially available ester.
